UNITED STATES PATENT OFFICE.

THOMAS S. BUFORD, OF JOPLIN, MISSOURI.

REFRIGERATING DISPLAY COUNTER.

Application filed June 12, 1926. Serial No. 115,595.

This invention relates to refrigerators and particularly to refrigerating display or show counters.

The general object of the present invention is to provide a display counter of this character particularly adapted for butchers and grocers, which is so constructed as to give a maximum display of goods contained within the refrigerator and at the same time provide for thoroughly good circulation of the cold air around the goods.

Another object is to provide a construction of this character which will not sweat.

A further object is to provide in a refrigerating display counter of this character means for supporting the ice which will permit the ice to be readily inserted within the ice chamber or removed therefrom and which will permit a ready cleaning of all parts.

Other objects have to do with the details of construction and arrangement of parts to appear more fully hereinafter.

My invention is illustrated in the accompanying drawings wherein:—

Figure 1 is a front elevation of a refrigerating display case constructed in accordance with my invention;

Fig. 2 is a rear elevation thereof;

Fig. 3 is a vertical longitudinal section;

Fig. 4 is a section on the line 4—4 of Figure 3;

Fig. 5 is a section on the line 5—5 of Figure 3;

Fig. 6 is a fragmentary horizontal section showing means for holding the ice container in adjusted position.

Referring to these drawings 10 designates the base of the display counter, 11 the end walls, 12 the top wall, and 13 pilasters which extend upward from the base and the top wall at front and rear, dividing the front and rear into three panels, as they may be termed. On the front of the display counter these three panels are filled each with a sheet of glass 14 and the top is provided with laterally disposed glass panels 14a. On the rear the middle panel is closed by two doors 15 and each lateral panel by a single refrigerator door 16. These doors are, of course, made in the usual manner of refrigerator doors so as to provide stepped faces extending into the stepped faces of the jambs of the door and the lintel thereof respectively.

Separating the interior of the ice box into three compartments are the intermediate

walls 17. These walls are cut away at their upper and lower ends as at 18 to provide for the circulation of air. Thus, there are three main compartments within the display case 60 designated A, B and C respectively, the compartment B being intended to receive ice, while the compartments A and C receive food. Disposed within the compartments A and C are the shelves 19 which may be of 65 any suitable number and which are supported in any suitable manner, these shelves being perforated to permit the passage of cold air, and the shelves being preferably formed of a single thickness of material 70 such as wood. These shelves may terminate short of the front of each compartment so as to permit the circulation of air or they may extend entirely across the compartment from front to rear and the circulation of air will 75 be secured by the perforations in the shelves. Inward of the walls 11 I provide vertically extending sheet metal plates 20, the forward and rear edges of which are inwardly flanged and attached to the end walls 11, 80 these plates 20 being nearly as wide as the width of the end walls and nearly as high as the end walls. These flanged plates 20 constitute air ducts open at top and bottom and extending down inward of the side 85 walls.

The compartment B is unbroken by shelves and extends vertically preferably the full distance between the top 12 and the base 10. Pivotedly swung within this compartment B is the ice container or tank 21 which is mounted upon trunnions 22 extending through the partition walls 17. The lower end of this ice container is rounded so that the container in cross section from front 90 to rear has preferably a U-shape, the upper margins of the side walls being outwardly flared as at 23. The size and proportion of this ice tank are such that it may be turned over upon its side and when so turned a side 95 wall of the ice tank will be closely adjacent the base, that is the floor of the display case, the flange 23 in this case extending downward and outward over the margin of the floor and permitting the easy insertion of a 100 cake of ice into the ice tank or the removal of ice therefrom. This tank is provided with some means permitting water to drip therefrom and to this end I provide a drip cock 24 in the bottom of the tank and a drip cock 25 spaced above the bottom of the tank 105 to any desired extent. By means of these

two drip cocks or drain cocks it is possible to regulate the height of water which may accumulate in the lower end of the ice tank and keep any depth of water desired or permit all of the water to run out. When the ice tank is turned into its vertical position the lower end of the ice tank is spaced from the bottom of the ice chamber and from the drip pan 26 carried thereon and bottles of ginger ale, pop, or even vegetables may be kept in this space but, of course, will have to be removed in order to permit the ice tank to be turned to its discharge position. By turning the ice tank to its discharge position it may be very readily cleaned which is a very important factor in the management of refrigerators. In order to hold the ice tank in any desired tilted position I mount upon one end wall thereof a lever 27 pivoted at 28 and this lever is notched at 29 at a plurality of points, these notches being adapted to engage with the jamb of the door frame and thus hold the ice tank in any tilted position. Thus, the ice may be slipped into the ice tank when the latter is in a horizontal position or when the ice tank is tilted from the vertical position and the notched lever or latch 27 will hold the tank under these circumstances.

It is to be particularly noted that the walls throughout, except the front wall which is formed of closed panels, are all of solid material and in actual practice the counter should be formed with 2×8 , 2×10 , or 2×12 lumber and the walls should be formed of tongued and grooved material glued together and insulated with three ply roofing paper or other insulating material between the walls.

The base, as illustrated, is supported above the floor by a skirting board 30, which is cut away at 31 to receive a drip pan 32 from which the drip from pan 26 may pass. It is to be noticed that the floor of this display counter is continuous from end to end and that the entire floor may be observed through the plate glass panels of the front walls. Preferably a metallic plate 33 having its ends upwardly bent is disposed against the

top of the ice chamber B, this plate being perforated. The purpose of this plate 33 and of the plates 20 is to keep the warm and cold air separated or, in other words, to cause circulation of the warm and cold air. The walls 17 which separate the ice compartment from the food compartments A and C are spaced at their middle portions from the top and bottom of the display counter and these two walls cause a double circulation of the cold and warm air, the cold air following downward in the ice chamber and passing laterally into the food chambers while the warmer air rises in the food chamber and passes laterally into the ice chamber where it again becomes cool.

While I have illustrated a construction in which a tank or other receptacle is provided for ice or ice and salt, I do not wish to be limited to this as an ice machine can be installed within the ice compartment. Because of the simplicity of its construction it is possible to build a display counter of this character at a much less cost than other display counters.

I claim:—

In a refrigerating display counter of the character described, an ice compartment, vertical partition walls at the ends of the same, the partition walls being spaced at their upper and lower ends from the bottom and top of the ice compartment, an ice receptacle pivotally mounted on said partition walls, the receptacle being approximately U-shaped in cross section and open at the top and having its forward wall angularly disposed and the pivotal axis for said ice receptacle being so disposed that the receptacle may be swung into a downwardly and outwardly inclined position or into a vertical position, and means for holding the receptacle in a vertical position or an angularly disposed position including a latch pivoted to one end wall of the receptacle and having ratchet notches engaging with the door jamb.

In testimony whereof I hereunto affix my signature.

THOMAS S. BUFORD.
